CLAIM

The ornamental design for a planar optical panel for a light fixture, as shown and described.

DESCRIPTION

FIG. 1 is a bottom isometric view of a planar optical panel for a light fixture.

FIG. 2 is another bottom isometric view of the planar optical panel of FIG. 1.

FIG. 3 is a bottom view of the planar optical panel of FIG. 1.

FIG. 4 is a cross-section view of the planar optical panel of FIG. 1, taken along line 4-4 in FIG. 3; and,

FIG. 5 is another cross-section view of the planar optical panel of FIG. 1, taken along line 5-5 in FIG. 3.

The cross-section views of the optical panel designs illustrate that, while the optical panel has an appearance of a three dimensional design when viewed from below, the optical panel is planar in appearance when viewed from the side.

The dot-dot-dash lines showing a light fixture is for the purpose of illustrating environmental structure and form no
